(57) **CLAIM**

The ornamental design for a hutch, as shown and described.

DESCRIPTION

FIG. 1 is a perspective view of a hutch.

FIG. 2 is a front elevational view of a hutch; and,
FIG. 3 is a side elevational view of a hutch with the opposite
side being a mirror image of the same.

The top and bottom of the hutch form no part of the claimed
design.

The broken lines in the drawings form no part of the claimed
design.
